Primary Examiner — Patricia Palasik(74) *Attorney, Agent, or Firm* — Waddey & Patterson, P.C.;
Lucian Wayne Beavers(57) **CLAIM**

What is claimed is the ornamental design for a base for a chisel holder, as shown and described.

DESCRIPTION

FIG. 1 is a front perspective view of the base for a chisel holder.

FIG. 2 is a front elevation view of the base for a chisel holder of FIG. 1.

FIG. 3 is a right side elevation view of the base for a chisel holder of FIG. 1.

FIG. 4 is a rear elevation view of the base for a chisel holder of FIG. 1.

FIG. 5 is a left side elevation view of the base for a chisel holder of FIG. 1.

FIG. 6 is a bottom view of the base for a chisel holder of FIG. 1; and,

FIG. 7 is a top view of the base for a chisel holder of FIG. 1.
